DESIGN FOR A CIGARETTE DISPENSER

David Nusbaum, Newark, N. J.

Application August 17, 1946, Serial No. 132,602

Term of patent 14 years

(Cl. D85—2)

To all whom it may concern:

Be it known that I, David Nusbaum, a citizen of the United States, residing in the city of Newark, county of Essex, and State of New Jersey, have invented a new, original, and ornamental Design for a Cigarette Dispenser, of which the following is a specification, reference being had to the accompanying drawing, forming part thereof.

In the drawing:

I claim:

The ornamental design for a cigarette dispenser, as shown.

DAVID NUSBAUM.
